UNITED STATES PATENT OFFICE

WILLIAM H. McCOLM, OF DENVER, COLORADO

ADJUSTABLE PACKAGE SEALING APPARATUS

Application filed August 24, 1929. Serial No. 388,090.

This invention relates to an adjustable sealing device and has for its principal object the provision of a device of this character which will efficiently operate to press 5 the flaps of box-board and corrugated board packages in place while the sealing cement is setting.

Another object of the invention is to so construct the device that it can be quickly 10 adapted to sealing packages of various shapes and sizes.

A further object of this invention is to so construct the device that a series of packages can be placed therein so that when the final 15 package has been placed the first package can be removed, thus making the operation of the apparatus practically continuous.

Other objects and advantages reside in the detail construction of the invention which is 20 designed for simplicity, economy, and efficiency. These will become more apparent from the following description.

In the following detailed description of the invention reference is had to the accompanying drawings which forms a part hereof. Like numerals refer to like parts in all views of the drawings and throughout the description.

In the drawings:

Fig. 1 is a perspective view of the complete invention in use.

Fig. 2 is an end elevation thereof.

Fig. 3 is a vertical section therethrough.

The invention comprises a pair of supporting standards 10 carried on cross feet 11. Extending between the standards 10 at the bottom is a bottom brace 12 and extending between the standards 10 at the top is a pair of cross members 13 and 14.

A series of vertical struts 15 extend between the cross members 13 and 14 and are clamped in place therein by means of clamp bolts 16. Immediately in front of each of the struts 15, a vertical sliding shaft 17 is positioned which terminates at its bottom in a flange 18 which in turn is secured to a pressure plate 19. The shafts 17 are constantly forced upwardly by means of compression springs 20 which surround them and

extend between the upper cross member 13 and a flange 21 formed on the shafts.

The shafts 17 can be forced downwardly by means of operating handles 22, one end of each of which is pivoted to each of the struts 15 as shown at 23. The pivoted extremities of the operating handles 22 are bent, as shown at 24, to form one member of a toggle joint. The other member comprises a link 25 which is secured at 26 to the shaft 17. The upward 60 movement of the levers 22 is limited by the upper cross brace 13. The downward movement thereof is limited by a stop bar 27 which extends entirely across the device and is secured to the fronts of the struts 15. 65

The packages to be sealed, such as indicated at 28, Fig. 1, are supported upon a shelf 29. The shelf 29 is carried upon a longitudinal shelf member 30 the extremities of which extend through vertical slots 31 in the supporting standards 10. Suitable braces 32 are provided to rigidly support the shelf 29 upon the longitudinal member 30. 70

Upon the external face of each of the standards 10 an endless chain 33 extends between an upper sprocket 34 and a lower sprocket 35. The upper sprocket 34 is secured on the extremities of a cross shaft 36 which extends entirely across the device. The lower sprockets 35 are simply idler 80 sprockets and may be secured to the standards 10 in any desired manner.

The shaft 36 may be rotated by means of an operating crank 37 secured to one of the sprockets 34 at one extremity of the apparatus. The longitudinal shelf member 30 is secured at its extremities, by means of attachment clips 38, to each of the chains 33. Thus any movement of the chains will be imparted to the shelf 29. The shelf 29 is maintained in any desired elevated position by means of a ratchet wheel 39 secured to the shaft 36 so as to co-operate with a suitable hand operated pawl 40. 90

Let us assume that packages of a certain 95 size are to be sealed. The operator places a trial package upon the shelf 29 and rotates the crank 37 to bring the package to a position slightly below the pressure plate 19, when in the raised position. He now sets the 100

shelf in this position by means of the pawl 40, and the machine is ready for use upon this size and type of package. This setting may be also accomplished without a trial 5 package by means of a scale 41 carried by one of the standards 10, upon which a shelf pointer 42 indicates the position of the shelf. Thus, the operator may know that a certain size of package requires a shelf setting of 10 "4 1/2". He can by means of the crank 37 quickly bring the shelf to this setting so that the apparatus will be ready for use.

The apparatus may be used for sealing both the bottoms and the tops of packages. 15 For instance, the package may be filled and the flaps at one end cemented in place, then inverted and the flaps on the other end cemented in place. It is then slid upon the shelf 29 immediately below one of the pressure plates 19. The handle 22 is forced downwardly to the broken line position of Fig. 3, causing the pressure plate to press or squeeze the package between it and the shelf 29. The 20 toggle action of the handle portions 24 and 25 in passing their dead center point, maintains the handle in the lowermost position against the stop 27, while the operator is placing the package under the next pressure plate. This operation is continued 25 throughout the length of the apparatus.

When a package has been placed under the last pressure plate and its operating handle 22 operated, the cement has usually set sufficient so that the package under the first plate 30 can be removed and replaced by a new package, thus making the operation of the apparatus substantially continuous.

As soon as the operating handles 22 are lifted from the stop bar 27 the springs 20 will 40 raise the shafts 17 so as to release the package and will maintain them in their raised position until again manually operated.

While a specific form of the improvement has been described and illustrated herein, it 45 is desired to be understood that the same may be varied, within the scope of the appended claims, without departing from the spirit of the invention.

Having thus described the invention, what 50 is claimed and desired secured by Letters Patent is:

1. An adjustable shelf for package sealing machines comprising: a pair of standards provided with a vertical slot; a shelf extending between said standards; a longitudinal member supporting said shelf and extending at its extremities through the slots in said standard; means carried by said standards for raising or lowering the extremities of 55 said longitudinal member so as to change the height of said shelf, said latter means comprising: endless chains; a cross shaft extending between said standards; sprockets carried by said cross shafts and arranged to support said chains; and means for rotating said

shafts, said longitudinal member being secured at its extremities to said chains.

2. An adjustable shelf for package sealing machines comprising: a pair of standards provided with a vertical slot; a shelf extending between said standards; a longitudinal member supporting said shelf and extending at its extremities through the slots in said standard; means carried by said standards for raising or lowering the extremities of 70 said longitudinal member so as to change the height of said shelf, said latter means comprising: endless chains; a cross shaft extending between said standards; sprockets carried by said cross shaft and arranged to support said chains; means for rotating said shafts, said longitudinal member being secured at its extremities to said chains; a ratchet wheel carried by said shaft and a pawl adapted to engage said ratchet wheel so as to prevent rotation of said shaft in one direction and maintain said shelf in any desired elevated position.

In testimony whereof, I affix my signature.

WILLIAM H. MCCOLM.
